United States Patent

Des. 238,783

Patented Feb. 10, 1976

238,783

COMBINATION STOVE AND HEATER

Peter Kilham, Barrington, R.I., assignor to
Droll Yankees, Inc.

Filed May 13, 1974, Ser. No. 469,335

Term of patent 14 years

Int. Cl. D23—03, 05

U.S. Cl. D23—97

FIG. 1

FIG. 2

FIG. 3

FIG. 4

FIG. 5

FIG. 6

FIG. 7

FIG. 1 is a front perspective view of a combination stove and heater showing my new design;

FIG. 2 is a front elevational view thereof;

FIG. 3 is a side elevational view thereof taken from the right with respect to FIG. 2;

FIG. 4 is a side elevational view taken from the left with respect to FIG. 2;

FIG. 5 is a rear elevational view thereof;

FIG. 6 is a top plan view thereof; and

FIG. 7 is a bottom plan view thereof.

The legs of the combination stove and heater have been shown fragmentarily in FIGS. 3 and 4 for ease of illustration.

I claim:

The ornamental design for a combination stove and heater, substantially as shown and described.
